UNITED STATES PATENT OFFICE.

WILLIAM H. GETTZ, OF PHILADELPHIA, PENNSYLVANIA, ASSIGNOR TO JAMES A. COUTTS, OF PHILADELPHIA, PENNSYLVANIA.

CARBURETER-LOCK.

1,250,299.

Specification of Letters Patent. Patented Dec. 18, 1917.

Application filed June 30, 1916. Serial No. 106,805.

To all whom it may concern:

Be it known that I, WILLIAM H. GETTZ, a citizen of the United States, residing at Philadelphia, in the county of Philadelphia and State of Pennsylvania, have invented certain new and useful Improvements in Carbureter-Locks, of which the following is a specification.

My invention consists of an improved form of carbureter lock, and is particularly serviceable for use on motor cars, motor boats, or any device employing internal combustion engines, however, it may be employed with advantage any place where it is desired to prevent access to a supply of gasoline or fluid of any description.

My invention is also used advantageously as a carbureter lock, and I have illustrated the same in connection with a carbureter such as is employed in connection with internal combustion engines.

One object of my invention is to provide a lock which may be opened when a pre-determined combination is secured by the movement of certain elements which have openings designed to register one with the other when the proper combination is attained.

A further object of my invention is to so construct the several parts that they may be easily operated by one who knows the desired combination.

Another object of my invention is to provide means for preventing accidental movement of the several parts due to vibrations.

A further object of my invention is that when it is used in connection with a carbureter, it will provide means for cutting off the general supply of gasoline, and in addition will operate the well known pin valve within the carbureter to prevent any gas which is in the supply chamber of the carbureter from moving into the mixing chamber of the carbureter.

These objects, and other advantageous ends which will be described hereinafter, I attain in the following manner, reference being had to the accompanying drawings in which—

Figure 1 is a sectional elevation of my invention connected to a carbureter, part of the carbureter being shown in outside view,

Fig. 2 is a fragmentary plan view of Fig. 1.

Fig. 3 is a sectional plan view taken on the line *a—a* Fig. 1.

Fig. 4 is a sectional plan view taken on the line *b—b* of Fig. 1 looking downwardly, showing the top of a flanged central valve which I employ, certain of the other elements of my invention being omitted for clearness.

Fig. 5 is a section taken on the line *b—b* of Fig. 1 looking upwardly and showing a disk.

Fig. 6 is a section taken on the line *c—c* of Fig. 1 looking upwardly and showing another disk which I employ.

Fig. 7 is a sectional plan view on the line *c—c* of Fig. 1 looking downwardly, showing the flanged top of a sleeve valve which forms a part of my invention, and

Fig. 8 is an elevation, partly in section, showing my invention provided with extended portions, which is desirable when the carbureter and lock are situated in a manually inaccessible position.

Referring to the drawings, 1 is the body portion of the carbureter having a supply chamber 2 and an inlet passage 3 for the gasoline or other fluid. This supply chamber has an enlarged portion 4 in which is positioned a float 5 made of cork, and in the present construction is ring shaped and surrounds a cylinder 6 which is provided with an intake passage 7 which leads to the mixing chamber which is within the member 8.

This intake passage 7 is flared at 9 and forms a valve seat as will hereinafter be more fully described.

The float 5 has a forked arm 10 which is pivoted at 11 to said body portion 1, and the yoked end of the arm 10 surrounds a valve 12 which is slidably mounted within a removable cap 13, in the present instance threaded into the body portion 1. The valve 12 is positioned directly above the inlet passage 3, and is moved downwardly to close said inlet passage when the gasoline within the enlarged portion 4 of the supply chamber raises the float 5 to a pre-determined level, thus cutting off further supply of gasoline through the inlet passage 3,

A main lock casing 14 is secured by bolts 15 and nuts 16 (see Fig. 2) to the body portion 1, and has a passage 17 which registers with the inlet passage 3. This passage 17 leads to a frusto-conical bore 18 in the main lock casing 14, there being a main inlet passage 19 in the casing 14 which also communicates with the frusto-conical bore 18. This main inlet passage 19 is connected with 10 the source of supply.

A sleeve valve 20 fits within the bore 18, and has ports 21 and 22 which when said valve is in the position shown in Fig. 1, register respectively with the main inlet 15 passage 19 and the passage 17. The sleeve valve 20 is internally bored to receive a tapered or frusto-conical central valve 23. This valve has a zigzag passage 24 extending transversely thereof, the ends of said 20 passage intersecting the outer surface thereof, and designed when said latter valve is moved in the position shown in Fig. 1, to register with the ports 21 and 22, so that when the parts are in the position illustrated, 25 gasoline or other fluid may pass inwardly through the inlet passage 19, port 21, passage 24, port 22, passage 17, and inlet passage 3 to the supply chamber 2 of the carburetor.

30 The sleeve valve 20 is provided with an annularly extending flange 25 which has an annular recess 26 and an upwardly projecting pin 27, said pin being fixed within the flange 25 and passing upwardly through 35 said annular recess 26.

An operating disk 28 has an annular projection 29 on its bottom surface which fits within the recess 26, and a series of holes 30 each of which is of similar contour and 40 designed to be fitted over the top of the pin 27 as illustrated, there being ten holes 30.

The upper surface of the disk 28 has a 45 number of indicating characters as illustrated, being represented by the numerals 1 to 9 and 0. Each one of these indications is directly above one of the holes 30, and there are a series of notches 31 in the periphery of the disk 28, there being one notch 50 for each indicating mark. These notches are designed to be engaged by the end of a retaining spring 32 which is secured to the top of the main casing 14.

The central valve 23 is reduced in diameter at 33, thereby forming a stem which projects through an opening in the disk 28, and is provided with an annular flange 34. This flange 34 has a pin 35 projecting upwardly therefrom, said pin being designed to engage any of a series of holes 36 in the 60 lower face of a disk 37, these holes being of similar construction to the holes 30 in the disk 28, there also being ten holes 36.

The upper surface of the disk 37 is provided with indicating marks similar to those 65 described in connection with the disk 28, and

the periphery of said disk 37 is notched at 38.

A retaining spring 39 which is secured to the main casing 14, is capable of engaging any of the notches 38. It will be understood 70 that the springs 32 and 39, in addition to retaining the disks 28 and 37 in proper position, also act as indicating pointers, so that a person can tell at a glance when the several elements are in the desired position. 75

A thumb screw 40 extends through the disk 37, and engages a threaded opening in the central valve 23, the purpose of said thumb screw being to secure the disk 37 to the annular flange 34. 80

The pin 27 has a set relation to the port 21 and the pin 35 has a set relation to the ends of the passage 24. In the same manner, each of the retaining springs 32 and 39 has a set relation to the main inlet passage 19 and the passage 17, so that since these relations are known, the disks 28 and 37 may be moved into different positions to set the combination, and to one who knows the relations of these elements one to the other, all the passages may be moved into alinement, after they have been moved out of alinement, to secure the proper alining of the several passages and ports to permit the gasoline or other fluid to flow through the 95 inlet 19 into the supply chamber 2.

The lower end of the central valve 23 has a threaded end 41, provided with a nut 42. This nut engages washers 43 and 44, the washer 44 being sufficiently large to cover the bore 18, thereby preventing any longitudinal movement between the valves and casing 14. 100

The central valve 23 is grooved or provided with a "flat" as clearly shown at 45 in Fig. 3, and the sleeve valve 20 is slotted throughout a portion of its circumference as shown at 46, said slot 46 and groove 45 being in register when the passages and ports are in alinement as above described. 105

A plunger 47 has a tongue 48 which is provided with cam edges 49 which normally project through the slot 46, and engage the flat cam provided by the groove 45 (see Fig. 3.) The plunger 47 is backed by an expansion spring 50, which engages the forward face of the body portion 1. This plunger 47 also has a stem 51 of small diameter, and this stem is slid able through the body portion 1 and provided with a tapered end 52. This tapered end 52 forms a valve, and is designed when the plunger and stem 51 are moved longitudinally, to engage the valve seat 9 of the intake passage 7 which leads to the mixing chamber, thus closing said intake passage and preventing the gasoline or other liquid from passing from the supply chamber to the mixing chamber. 115

The two rounded edges 46^a at the ends of the slot 46 are so arranged with respect to 120

the cam edges 49 that they will engage said edges when the valve is turned and push the plunger 47 longitudinally.

It will thus be understood that when either or both of the valves 20 or 23 are turned from the positions illustrated in Figs. 1 and 3, the plunger 47 will be moved longitudinally to seat the valve 52 of the stem 51, and thereby close the intake passage 7. At the same time, the passages 19, 24, and 17, and the ports 21 and 22 will be moved out of alinement, thereby preventing any more gasoline from entering the supply chamber 2, thus it will be understood that my invention not only effectively locks the main inlet passage from the source of supply, but also prevents any gasoline or other liquid which is already within the supply chamber of a carburetor from entering the mixing chamber wherein it is vaporized and conducted to the internal combustion engine, so that if my invention is applied to an automobile, it is impossible to run the automobile even for a short distance.

While I have illustrated my invention in connection with one form of carburetor in common use, it will be noted that my invention may be used with any of the well known types of carburetors which include a supply chamber and a member for conducting the fluid from the supply chamber to the mixing chamber. It is merely necessary to provide a passage for the stem 51 and arrange this passage in alinement with the intake passage from the supply chamber to the mixing chamber.

In Fig. 8, I have illustrated my invention as it may be applied when the carburetor is located in an inaccessible position, and where it would be unhandy to locate the several disks near the main casing 14 of the lock.

In this form, I locate the disk 37 on an annular flange 53 and connect the central valve 23 and the sleeve valve 20 by means of rod 54 and tube 55. The rod 54 is connected to the flange 53, and the tube 55 has an annular flange 56 connected thereto, which in other respects is similar to the flange 25 above described, and has detachably secured thereto by pin and hole connection similar to the disk 28 and flange 25, a disk 57.

In this construction, the disk 37 and disk 57 are each provided with indicating marks and have their peripheries notched and engaged by springs 58 and 59 respectively which are secured to a supporting bracket 60. With this construction, the disks 37 and 57 and their adjacent parts, may be located above the hood or dash board of an automobile in a position easily operative, and will control the valves which are within the interior of the car.

Furthermore, in this construction I may

dispense with the disk 28, since the disk 57 has the same function as does the disk 28, otherwise this form of my invention is similar to that described in connection with the other figures of drawing.

In some instances where it is desired to provide a lock merely for the flow of fluid through a passage, the plunger 47 and its co-operative parts may be eliminated and the remaining parts will operate to effectively prevent the passage of fluid from the source of supply.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A lock comprising a main casing provided with passages and a bore intersecting said passages, a sleeve valve fitting said bore and having ports movable into register with said passages, a central valve fitting within said sleeve valve and having a passage extending therethrough movable into register with the ports of said sleeve valve, an indicating member, a pin and hole connection between said indicating member and the sleeve valve operative to relatively change the position of said member and sleeve valve, an indicating member having pin and hole connection with the other of said valves operative to relatively change the position of said latter-mentioned member and valve, and means for locking engagement with said indicating members determining the alinement of said passages and ports, said means being operative to hold said members against accidental movement after the latter have been moved to a pre-determined position, substantially as described.

2. A lock comprising a main casing provided with passages and a bore intersecting said passages, a sleeve valve fitting said bore and having ports movable into register with said passages, a central valve fitting within said sleeve valve and having a passage extending therethrough movable into register with the ports of said sleeve valve, an indicating disk having holes therein, a pin secured to said sleeve valve and designed to engage any of said holes, a pin secured to said other valve, an indicating member having holes therein designed to be engaged by said latter pin, indicating marks on said members, fixed means visible from the outside of said casing for designating the position of the passages in said main casing,

4
said members being movable with respect to said latter means to bring said ports and passage of the valves in alinement with the passages of said main casing, said latter 5 means being operative to hold the indicating means against accidental movement, said alinement being determined by the relation of said pins to the respective indicating members and the relation of said members 10 with said latter means, substantially as described.

3. A lock comprising a main casing provided with passages, and a bore intersecting said passages, a sleeve valve fitting said 15 bore and having ports movable into register with said passages, a central valve fitting within said sleeve valve and having a passage extending therethrough movable into register with the ports of said sleeve valve, 20 said sleeve valve having an annular flange, and a pin secured therein, a disk having a plurality of holes designed to be detachably engaged by said pin, indicating marks on said disk, and a retaining member for direct 25 locking engagement with said disk thus holding said disk against accidental movement after the latter has been set, substantially as described.

4. The combination with a casing including 30 a fluid supply chamber having an inlet and an outlet passage communicating therewith, a valve movable to cut off said inlet passage, a plunger having a valve for closing said outlet passage, and means on said 35 first valve for moving said plunger to close said outlet passage, said first valve providing means when so moved to close said inlet passage, substantially as described.

5. The combination with a casing including 40 a supply chamber having an inlet and an outlet passage communicating therewith, a valve movable to close said inlet passage, a plunger having a valve for closing said outlet passage, means on said first valve for 45 moving said plunger to close said outlet passage, said first valve providing means when so moved to close said inlet passage, and means operative to move said plunger and thereby open its valve when said first valve 50 is moved to open the inlet passage, substantially as described.

6. The combination with a casing including 55 a supply chamber having an inlet and an outlet passage communicating therewith, a valve movable to close said inlet passage, a plunger having a valve for closing said outlet passage, means on said first valve for 60 moving said plunger to close said outlet passage, said first valve providing means when so moved to close said inlet passage, means

operative to move said plunger and thereby open its valve when said first valve is moved to open the inlet passage, said plunger having a cam shaped end for engagement with a flat portion on said first valve, substantially as described. 65

7. The combination with a casing including a supply chamber having an inlet and an outlet passage communicating therewith, a sleeve valve having ports therein movable into and out of alinement with said inlet passage, a central valve having a passage movable into and out of alinement with the ports of said sleeve valve, said sleeve valve having a slot therein in register with a 75 groove in said central valve when the ports and passage of the respective valves are in alinement, a plunger having a portion movable through said slot and into said groove, a valve secured to said plunger and operative 80 when moved longitudinally to open and close the outlet passage, said first two valves being movable to actuate said plunger to close its valve and to cut off the inlet passage, and means for moving said plunger 85 valve to open the outlet passage when said first two valves are moved to position their passages and ports in alinement with said inlet passage, substantially as described.

8. The combination with a casing including 90 a supply chamber having an inlet and an outlet passage communicating therewith, a sleeve valve having ports therein movable into and out of alinement with said inlet passage, a central valve having a passage 95 movable into and out of alinement with the ports of said sleeve valve, said sleeve valve having a slot therein in register with a groove in said central valve when the ports and passages of the respective valves are in 100 alinement, a plunger having a portion movable through said slot and into said groove, a valve secured to said plunger and operative when moved longitudinally to open 105 and close the outlet passage, said first two valves being movable to actuate said plunger to close its valve and to cut off the inlet passage, and a spring for moving said plunger valve to open the outlet passage when 110 said first two valves are moved to position their passages and ports in alinement with said inlet passage, substantially as described.

In testimony whereof I have signed my name to this specification in the presence of two subscribing witnesses.
